UNITED STATES PATENT OFFICE.

HENRY F. POPE, OF CLEVELAND, OHIO, ASSIGNOR TO THE NATIONAL
MALLEABLE CASTINGS COMPANY, OF CLEVELAND, OHIO, A COR-
PORATION.

CAR-DOOR LOCK.

No. 796,978.

Specification of Letters Patent.

Patented Aug. 8, 1905.

Application filed July 26, 1904. Serial No. 218,243.

To all whom it may concern:

Be it known that I, HENRY F. POPE, of Cleveland, Cuyahoga county, Ohio, have invented a new and useful Car-Door Lock, of which the following is a full, clear, and exact description, reference being had to the accompanying drawings, forming part of this specification, in which—

Figure 1 shows in elevation a car-door lock constructed in accordance with my invention. Fig. 2 is a view of the bolt before it is finally secured to the stud on which it slides, and Fig. 3 is a vertical cross-section of the base-plate stud and bolt when the bolt has been secured to the stud.

My invention is an improvement on the car-door lock described in a patent of Hopkins & Tesseymen, No. 455,686, dated July 7, 1891. The device shown in that patent comprises a longitudinally-slotted bolt slidingly mounted upon a fixed stud, and as it has been made heretofore the stud has been formed in a separate piece, which has been inserted through the slot of the bolt into a hole in the base-plate and has been secured to the base-plate by upsetting its inner end in the manner of a rivet, the head at the outer end of the stud fitting against the front of the bolt and confining it. When the workmen are assembling the parts, the studs are apt to be imperfectly upset, and when this occurs it produces a defective lock. These difficulties are entirely avoided by my invention, in which the stud is made integral with the base-plate—

that is to say, formed on it or permanently fixed to it during the act of casting—the bolt being applied by making it of malleable metal with its slot wider than the head of the stud, so that it may be placed loosely thereon, and then squeezing the sides of the bolt together toward the stud and back of its head, so as to confine it thereon.

In the drawings, 2 is the base-plate, and 3 is the stud, which is cast integral therewith and has a head 3'. The sliding bolt 4 is adapted to enter the staple 5 and to hold the hasp 6. This bolt is made of malleable metal, preferably malleable cast-iron, and is made originally with the sides of its slot farther apart than the width of the head 3', so that it may be placed loosely on the stud, as shown in Fig. 2. When it has been so placed, the sides are squeezed toward each other, so as to bring them back of the head and to hold the bolt permanently and slidingly upon the stud.

I claim—

A lock having a base-plate and an integral headed stud, and a malleable bolt having a longitudinal slot which fits the stud back of the head and is compressed to a less width than the head throughout the length of the slot; substantially as described.

In testimony whereof I have hereunto set my hand.

HENRY F. POPE.
